UNITED STATES PATENT OFFICE.

CONRAD HUBERT, OF CHATHAM BOROUGH, NEW JERSEY.

PORTABLE ELECTRIC LIGHT.

1,157,395.

Specification of Letters Patent.

Patented Oct. 19, 1915.

Application filed December 16, 1914. Serial No. 877,477.

To all whom it may concern:

Be it known that I, CONRAD HUBERT, a citizen of the United States, residing at the borough of Chatham, in the county of Morris and State of New Jersey, have invented certain new and useful Improvements in Portable Electric Lights, of which the following is a specification, reference being had therein to the accompanying drawings, forming part thereof.

My invention relates to portable electric lights suitable for carrying about in the pocket or otherwise and adapted to be held in the hand in use, such electric lights being commonly known as flash lights.

My invention more particularly relates to that type of these lights known as tubular flash lights, and to that kind of flash lights (tubular and other) having a metal shell constituting the principal part of the casing and forming a part of the electrical circuit.

In tubular flash lights the battery usually consists of a series of dry cells placed end to end in the usual insulating covering or container, which is simply a thick paper tube open at both ends, so that the carbon electrode of the uppermost cell may make contact with the central terminal of the lamp, and the zinc electrode cup of the lowermost cell will be exposed at the bottom, where it is electrically connected, by means of a coiled compression spring, with a metal cap forming a removable closure for the casing. A miniature incandescent electric lamp is carried by and is commonly in electrical connection with a metallic reflector which carries the metallic screw-threaded socket of the lamp, and which is commonly held in place by the lens and the lens-holding ring, the latter being screw-threaded over an exposed metal end part of the casing shell. The main part of the tubular shell of the casing is sometimes of non-conductive material and sometimes of metal. With the lamp in electrical connection with the conductive reflector and the battery in electrical connection with the bottom end cap, as above noted, it becomes necessary and has been the practice to insulate the lamp-carrying conductive reflector from the battery-connected bottom cover cap and to provide for bridging this insulation by means of manually controlled circuit completing means. It is highly desirable that only one battery terminal shall be exposed at the outside of the casing, as otherwise the two

exposed terminals might become bridged accidentally, and to accomplish this result it has been the practice to insulate the reflector at the inside of the casing from the exposed lens-holding metal ring and also from the usual exposed metal end part which carries the lens-holding ring. An example of such a construction with an all metal shell is disclosed in British Patent No. 9050 of 1911.

Objects of my invention are simplicity of construction, inexpensiveness of manufacture, durability, certainty of operation and of maintenance in operable condition, and other more particular objects or advantages which will hereinafter appear.

My invention includes features of construction and combinations of parts, as will appear from the following description.

I shall now describe the portable electric light illustrated in the accompanying drawings embodying my invention and shall thereafter point out my invention in claims.

Figure 1 is a central longitudinal section with parts in elevation, of a tubular portable electric light embodying my invention, with the circuit in the closed condition. Fig. 2 is an elevation, partly in section and with parts omitted, as seen from above in Fig. 1. Fig. 3 is a transverse section on a plane indicated by the line 3—3 of Fig. 1 as viewed from the right. Fig. 4 is a section similar to Fig. 1 on a larger scale with parts omitted and with the circuit in the open condition.

The tubular portable electric light or flash light embodying my invention illustrated in the accompanying drawings has a casing provided with a metallic screw-threaded lamp socket 1 carried by and insulated from a metallic reflector 2. The conductive lamp socket 1 passes through a central hole in the conductive reflector 2 and is securely and firmly held in place by outer and inner retaining flanges, as shown in the drawings, one of the retaining flanges, for example, the inner one, being formed by upsetting the metal after the lamp socket 1 is in place. The lamp socket 1 is shown as insulated from the reflector 2 by means of an insulating ring or collar 3 in the opening in the reflector, an insulating washer 4 outward from the reflector 2 and insulating ring 3 and at the inner side of the outer flange of the lamp socket 1, and an insulating disk 5 surrounding the inner portion of the ring or

collar 3 at the inner side of the reflector 2. A contact member shown as a slightly dished metal disk or plate 6 is held firmly in place and in electrical connection with the lamp socket 1 by the inner flange of such socket and is insulated from the reflector 2 by the above described insulating means for the lamp socket 1. It will be seen that the flanged lamp socket 1 firmly grips and 10 clamps together the reflector 2, the conductive contact plate 6 and the interposed insulation, and also is itself firmly and securely held in place. I have found that paper is a good material for the insulating 15 washer 4 and that vulcanized fiber is suitable for the insulating collar 3 and insulating disk 5.

An ordinary miniature incandescent lamp 7 is shown as screwed into the conductive 20 lamp socket 1, so that its usual outer annular contact terminal forming the base of the lamp is in electric connection with the conductive lamp socket 1 and contact plate 6. In view of the fact that the conductive 25 lamp socket 1 is insulated from the conductive reflector 2, there is no need, as has heretofore been done, to insulate the reflector 2 from its usual metal supports.

In the embodiment of my invention shown 30 in the drawings, a metal inclosing shell is employed and is shown as including a main tubular part 8 and a usual bell-shaped outer end part 9, telescoping over and rigidly secured to the tubular part 8. A usual lens 35 10 is carried by a usual exposed metal ring or band 11 shown as screw-threaded in the usual way over the outer end of the exposed metal end part 9. The lens 10 and its supporting band 11 hold the reflector 2 in place 40 on the metal end part 9. In this connection it will be noted that the rim of the metal reflector 2 is in electrical conductive connection with the exposed lens-carrying band 11 and exposed screw-threaded metal 45 end piece 9. Commonly heretofore the rim of the reflector has been insulated from corresponding metal end parts, and sometimes in such instances the tubular shell part, corresponding to the tubular shell part 8, has 50 been of metal and sometimes of insulating material.

The rear end of the tube 8 has a usual screw-threaded band 12 fixed thereon for the reception of a usual end cap 13 which 55 is provided at the inside with a usual battery-supporting conductive coiled thrust spring 14.

A battery of common form, shown as comprising three dry cells 15 placed end to end and contained in a usual paper insulating tube 16, is shown in position in the casing. The carbon terminal of the cell adjacent to the lamp is in contact with the central terminal of the lamp and the metal socket 1 is 60 the other terminal of the lamp. The other

terminal of the battery, the zinc cup of the cell at the rear end of the casing, is in contact with the conductive thrust spring 14, which is metallically connected to the whole metal casing, and the flow of current is therefore only interrupted at the insulation between the reflector 2 and lamp socket 1. To obtain the closed circuit condition, for lighting the lamp 7, manual means are provided for bridging the insulation of the lamp socket 1, and for this purpose a movable circuit closer is mounted on the shell tube 8. As shown, the tube 8 has a longitudinal slot 17 therein forming a guide-way for tubular rivets 18 which secure together 75 a slidable manually actuatable circuit closing member 19 at the outside of the tube 8 and a longitudinally movable contact strip or contact finger 20 at the inside of the tube 8. A strip 21 of fiber or the like is held by the rivets 18 between the slidable member 19 and the tube 8 to prevent the scratching of the polished outer surface of the metal tube 8 by the sliding of the circuit closing member 19. The slidable member 19 is shown 80 as provided with a rounded projection for easy manual actuation.

The contact strip or finger 21 extends forward within the tube 8 beyond the battery cells 15 and is shown as turned inward at a 95 slightly obtuse angle, so as to overlap and engage the contact plate 6 in the closed circuit position of the parts, as appears in Figs. 1, 2 and 3 of the drawings, thus completing the battery circuit from the lamp socket 1 through the contact plate 6 and contact strip 21 to the metal tube or shell 8. Movement of the outer slidable member 19 rearward or backward will withdraw the contact finger 21 from engagement with the contact plate 6, as appears in Fig. 4, and will thus establish the open circuit condition. The slidable circuit closing parts will be retained by friction at either the open or the closed circuit position so as to indefinitely maintain either of these circuit conditions.

It is obvious that various modifications may be made in the construction shown in the drawings and above particularly described within the principle and scope of my invention.

I claim:

1. A casing for a portable electric light including a conductive reflector provided with a socket-receiving opening, a conductive lamp socket in the opening and having retaining flanges at both sides of and overlapping upon the reflector, and insulating means interposed between the lamp socket and the reflector and clamped upon the reflector by the flanges of the lamp socket to hold the insulating means and lamp socket in place on the reflector and to insulate the lamp socket from the reflector.

2. A casing for a portable electric light including a conductive reflector provided with a socket-receiving opening, a conductive lamp socket in the opening and having
5 retaining flanges at both sides of the reflector, insulating means interposed between the lamp socket and the reflector and clamped upon the reflector by the flanges of the lamp socket to insulate the lamp socket
10 from the reflector, and a conductive contact

plate held in place by one of the flanges of the lamp socket in electrical connection therewith and insulated from the reflector by said insulating means.

In testimony whereof I have affixed my 15
signature in presence of two witnesses.

CONRAD HUBERT.
